DEEP WELL FLUID MOTOR

Charles C. Carlisle, Nowata, Okla.

Application February 15, 1934, Serial No. 711,333

8 Claims. (Cl. 103—46)

This invention relates to the art of pumping fluids from wells and particularly to the art of pumping oil from oil wells.

The customary method of pumping oil from a well is to lower a pump into the well and to operate it through mechanical linkage from the top of the well. The equipment necessary to operate the pump is called a "steel front" and usually comprises many parts, such as a walking beam, 5 a pitman rod, a crank and crank shaft, a geared revolving clutch and various pulleys, belts, etc. It is also necessary to have an engine, an electric motor or other power unit at the top of each well, and a suitable building to house the engine, belts, 10 pulleys, and other parts. The pump is operated by a string of rods extending from the top of the well to the pump and in cases where the well is very deep, the string of rods must be made up of rods of different sizes, with the larger rods 15 at the top, to carry the weight of the rods below as well as the column of oil.

The equipment which is required for each well is not only expensive to install but it is costly to operate and it is inefficient. In fact, present 20 pumping methods are not practical at all for wells of great depth. The weight of the string of rods and the weight of the oil lifted from the well is so great that it is not uncommon to have a stretching of the string of rods amounting to 25 37", or more, at each stroke of the pump, when pumping is taking place at a greater or less number of strokes per minute than the exact number which will synchronize with the stretch of the parts. Since very few pumps are timed to synchronize, the effective pumping stroke in the 30 working barrel at the bottom of the well is usually only that portion of the stroke in excess of 37".

My invention provides a method of, and apparatus for, pumping oil from wells, which entirely eliminates the necessity of using the customary equipment referred to above and thereby eliminates its attendant expense and disadvantages. The invention, however, is not limited to the 40 pumping of oil from wells but contemplates the pumping of any fluid from its well.

In accordance with my invention a fluid operated motor, so designed as to be capable of being lowered into a well, is mechanically and closely coupled to a pump and the two are lowered into the well. Fluid under pressure is pumped down the well to the motor to operate it and thereby operate the pump. In the preferred 45 form of the invention the fluid being pumped from the well mixes with the exhaust motive fluid

from the motor and the mixture of the two is discharged at the top of the well. For this reason the motive fluid should be of the same character as the fluid to be pumped from the well. In other words, if the material being pumped 5 from the well is oil, then oil should be used for the motive fluid, and likewise if water is being pumped from the well, water should be used for the motive fluid.

The principal object of the invention is to provide an improved method of and apparatus for pumping fluid from wells, and particularly for pumping oil from oil wells.

Another object of the invention is to pump oil from wells by a method and apparatus which will 10 eliminate the necessity of using the special equipment now customarily employed at the top of each well and which will thereby eliminate the expense 15 and disadvantages of such equipment.

Another object of the invention is to provide 20 an improved method of, and apparatus for pumping fluids from wells in which the efficiency of the apparatus will not be decreased by stretching of the parts due to excessive strains being placed upon them.

A further object of the invention is to provide 25 an improved compact motor-pump combination so designed as to be capable of use in limited spaces, such as in oil wells.

Various other objects of the invention will 30 hereinafter appear.

The accompanying drawings illustrate the improved method and one form of apparatus for carrying it out.

In the drawings:

Fig. 1 is a broken sectional elevation of the 35 improved apparatus showing it positioned in a well casing;

Fig. 2 is a vertical section of that part of the apparatus in which is located the valve mechanism for controlling the admission of motive 40 fluid to and its exhaust from the motor cylinder;

Fig. 3 is a broken vertical section of that part 45 of the apparatus which subjoins the part shown in Fig. 2 and shows the motor cylinder and the piston of the motor;

Fig. 4 is a transverse section taken on the line 4—4 of Fig. 2;

Fig. 5 is a broken vertical section of a still lower portion of the apparatus showing the pump 50 piston, the upper part of the pump cylinder and the upper valve mechanism of the pump. In this figure the motor piston is again shown to illustrate its relation to the parts of the pump.

Fig. 6 is a broken vertical section again show- 55

ing the pump piston and in addition illustrating the lower part of the pump cylinder and the lower valve mechanism of the pump, and

5 Figs. 7, 8 and 9 are simplified explanatory views, partly in section and partly in elevation showing the motor piston and the parts of the motor valve mechanism in various positions to make the operation of the motor clear.

10 In the preferred form of the apparatus the pump is a reciprocating double acting pump whose piston is mechanically connected with the piston of the motor which is positioned immediately above the pump. Motive fluid, such as oil, when oil is being pumped from a well, or 15 such as water when water is being pumped from a well, is pumped down the well to the motor through a central string of tubing. A main slide valve, which is itself actuated by an auxiliary motor, controls the admission of motive fluid to 20 and its exhaust from, the motor cylinder. When this valve admits motive fluid to the motor cylinder below the piston the piston rises and when it nears the upper end of its stroke it causes a pilot valve to be actuated which in turn causes 25 the auxiliary motor to operate and thereby shift the position of the main slide valve. This shifting of the main valve reverses the direction of flow of the motive fluid to the motor cylinder so that the motor piston then moves down and near 30 the end of its down stroke it again causes the pilot valve to be actuated to again effect operation of the auxiliary motor to thereby return the main slide valve to its original position.

35 The pump piston reciprocates as a unit with the motor piston, and at each stroke it draws into the pump cylinder at one side of the piston oil from the well, and forces out of the pump cylinder at the other side of the piston the oil that was drawn into the cylinder on the previous 40 stroke. The oil discharged by the pump is forced upwardly through an annular passage between two strings of tubing where it meets the oil exhausted from the motor and the mixture of the two is forced to the top of the well through an 45 annular passage surrounding the above mentioned central string of tubing through which the motive fluid is supplied to the pump.

50 Before describing the details of the apparatus reference is made to Fig. 1 for an understanding 55 of the relative arrangement of the various groups of parts. The casing of the well is indicated at 1. All parts of the apparatus are housed within an external string of tubing 2 which extends the full length of the apparatus down to a packer 3 inserted between the tubing 2 and a tube 4 through which fluid is admitted from the well to the pump. The motor piston is indicated at A and the valve mechanism for the motor is associated with and housed in the housing B. The 60 motive fluid is admitted to the valve mechanism in the housing B and to the motor through an inner string of tubing 5, and the exhaust from the motor together with the fluid pumped from the well is forced upwardly through the annular space between the inner string of tubing 5 and the outer tube 2. The pump cylinder is shown at C and the pump piston at D. The pump piston D is mechanically connected with the motor piston A by means of a rod 60. The valve mechanism for the pump is housed in the parts devoted generally at E and F.

65 Figs. 2 and 3 in conjunction show the details of the motor and the valve mechanism for the motor. The inner tubing 5 is threaded into engagement with a tubular member 7 which in turn

is threaded to a tubular member 8. These members 7 and 8 are parts of the housing B (Fig. 1). Within the central bore of the member 8 is a cylindrical main slide valve 9. The movement of the main slide valve 9 is effected by an auxiliary 5 motor comprising a cylinder 10 and a piston 12. The cylinder 10 is formed in a member 11 threaded to the part 8. The member 11 is also a part of the housing B (Fig. 1). The piston 12 of the auxiliary motor is rigidly connected by means of 10 two pipes 13 and 14 with the lower end of the main slide valve 9. The pipe 14 communicates at its upper end with a central bore 15 in the slide valve 9 through a port 16 in the slide valve. The lower end of the pipe 14 is controlled by an adjustable needle valve 17 and communicates with the space 18 below the piston 12 of the auxiliary motor. The pipe 13 has a port 19 which communicates with the space above the piston 12 of the auxiliary motor. At its upper end the pipe 20 13 communicates with a longitudinal bore 20 in the main slide valve, this bore having a port 21 communicating with the central bore 15 of the main slide valve. It will be understood that the auxiliary piston 12, together with the pipes 13 25 and 14 reciprocate as a unit with the main slide valve 9. The pipes 13 and 14 slide through openings in the upper part of the member 11 and are properly sealed by means of gaskets 22.

30 Within the central bore 15 of the main slide valve 9 there is a cylindrical pilot valve 23 the function of which is to control the operation of the auxiliary motor 10-11 which in turn actuates the main slide valve. The pilot valve 23 is carried by a member 25 which is rigidly coupled 35 with an upwardly extending sleeve 26. The member 25 carries a pin 27 to which are pivoted two short toggle links shown at 28 and 29. The outer end of the toggle link 28 is connected by means of a link 30 to the main slide valve 9 as shown at 40 31 and the outer end of the toggle link 29 is connected by means of a similar link 32 to the main slide valve 9 as shown at 33. A spring clip 34 normally retracts the links 30 and 32 towards the sides of the member 25 which carries the pilot 45 valve.

50 The piston A of the main motor (Fig. 3) has rigidly secured to it a rod 35 which extends up through a central bore in the pilot valve 23 and has a sliding fit therein. It also slides through a central bore in the pilot valve carrying member 25, and extends upwardly into the tube 26. At a point intermediate the ends of the tube 26 the rod 35 has secured to it a collar 36. Between the upper edge of the collar 36 and an abutment 55 37 carried by the tube 26 is a coil spring 38. A similar coil spring 39 is located between the lower edge of the collar 36 and the upper end of the pilot valve carrying member 25.

60 When the parts of the motor are in their respective positions shown in Figs. 2 and 3 the motor piston A is at the bottom of its stroke. Motive fluid is forced down to the motor through the inner tubing 5 as indicated by the full line arrows 65 in Fig. 2. It passes into diagonal ports 40 in the housing member 8. The upper ends of these ports communicate with the bore in which the main slide valve 9 slides and are now open by reason of the fact that the slide valve 9 is in its lowermost position. The motive fluid then passes downwardly between two concentric tubes 41 and 42 secured to the housing member 8 and is then admitted to the motor cylinder below the piston A through ports 43 (Fig. 3). The piston A of the motor, therefore, starts to move upwardly. 70 75

the motive fluid above the piston A, being forced up between the tube 41 and the housing member 11 of the auxiliary motor, as shown by the dotted line arrows in Figs. 2 and 3. When it reaches the housing member 8 of the main slide valve 9 it passes through ports 43' into an annular space 44 surrounding the main slide valve 9. The ports 43' are now open due to the fact that the main slide valve 9 is in its lowermost position. The 5 exhaust fluid then passes into diagonal ports 45 in the housing member 8 of the main slide valve and is discharged under a circular check valve 46 into the annular space between the housing member 7 and the tubing 2. It continues upwardly through the annular space between the tubing 2 and the inner tubing 5 and is discharged at the top of the well.

As the motor piston A moves upwardly it pushes the rod 35 up until its collar 36 sufficiently compresses the spring 38 to cause the sleeve 26 and also the pilot valve carrying member and pilot valve 23 to move upwardly with a sudden movement. The main valve 9 during this action remains stationary. The pin 27 in moving up with the pilot valve merely expands the toggle links 28 and 29 and moves them from the position shown in Fig. 2 to the position shown in Fig. 7 whereupon the upward movement of the pilot valve is arrested. During this change of position 25 of the toggle links the links 30 and 32 are first moved laterally away from the pilot valve carrying member 25 and are then again retracted towards it by the spring clip 34. The pilot valve now assumes, with respect to the main slide valve 30 9, the position shown in Fig. 7 in which it allows motive fluid in the space below the main slide valve 9 to pass through the port 16 then down through the pipe 14 into the space 18 below the piston 12 of the auxiliary motor. It should here be pointed out that the space below the main 40 slide valve 9 is always in communication with the incoming motive fluid due to the provision of one or more vertical bores 47 located in the main slide valve as shown in the sectional view of Fig. 4. The motive fluid thus admitted below the piston 12 of the auxiliary motor forces this piston upwardly while the motive fluid above this piston (exhaust fluid) is discharged through the port 19 in the pipe 13 and upwardly through the pipe 13, through the passage 20 in the main slide valve, out through the port 21 into an annular space 48 surrounding the pilot valve, then out through a radial port 49 in the main valve to the annular space 44 surrounding the main valve, thence out through diagonal ports 45, under circular check valve 46 and upwardly through the annular space between the tubes 2 and 5 following the path of the exhaust fluid from the main motor. As the piston 12 of the auxiliary motor moves upwardly it moves with it the main slide valve 9. The valve 9 in moving up will carry with it the pilot valve 23 due to the toggle links 28 and 29 and the links 30 and 32. The parts will then assume the respective positions shown in Fig. 8. The main valve 9 is now in a position to reverse the direction of flow of the motive fluid to the main motor. The port 43', connecting the cylinder of the main slide valve with the space above the motor piston A, now lies below the slide valve 9, as shown in Fig. 8, and motive fluid is admitted through this port to the space above the piston A thereby forcing it downwardly. The motive fluid below the piston A (now exhaust fluid) escapes through the ports 43 into the annular space between the tubes 41 and 42 and

moves upwardly through the diagonal ports 40, then into the annular space 44 surrounding the main slide valve and is discharged into the inclined ports 45. It then passes under the circular check valve 46, and moves upwardly through 5 the annular space between the tubes 2 and 5. As the piston A moves down, the collar 36 compresses the spring 39 thereby moving downwardly, with a sudden movement, the pilot valve carrying member 25 and the pilot valve until the 10 toggle links 28 and 29 move from the position shown in Fig. 8 to that shown in Fig. 9, the main valve 9 remaining stationary during this operation. The pilot valve 23 is now returned to its lowermost position relative to the main valve as 15 shown in Fig. 9 and motive fluid is admitted through the port 21 and pipe 13 to the space above the piston 12 of the auxiliary motor. This causes the piston 12 to move downwardly, the motive fluid below the piston 12 (now exhaust 20 fluid) being discharged upwardly through the pipe 14, through the port 16 into the annular space 48 around the pilot valve, thence out through port 49 into the annular space 44 around the main valve 9. It is then discharged upwardly 25 through the inclined ports 45 and passes under the circular check valve 46 into the annular space between the tubes 2 and 5. The downward movement of the piston 12 of the auxiliary motor returns the main valve 9 to its original position and 30 this movement of the valve 9 carries with it the pilot valve 23.

This completes one cycle and the parts are now again in their respective positions shown in Figs. 2 and 3.

It will now be seen that the movement of the main piston A of the motor near the end of each stroke compresses one or the other of the coil springs 38 and 39 and this causes the pilot valve to move suddenly without moving the position 40 of the main slide valve. The shifting of the pilot valve to its new position causes the auxiliary motor to operate and to shift the position of the main valve. The movement of the main valve to its new position reverses the direction of flow 45 of the motive fluid and causes the piston of the main motor to move in the opposite direction until it again shifts the position of the pilot valve without changing the position of the main valve whereupon motive fluid is admitted to the 50 auxiliary motor to shift the main valve and carry with it the pilot valve and thereby again reverse the direction of flow of the motive fluid.

The pump portion of the apparatus is shown in detail in Figs. 5 and 6. A rod 50 rigidly connects 55 the piston A of the motor with the piston D of the pump so that the pump piston reciprocates in unison with the motor piston. When the pump piston D moves upwardly fluid passes from the well into the central tube 4 which extends down 60 to the fluid in the well. It then passes upwardly under a circular check valve 52 into the pump cylinder 53. During the upward movement of the pump piston D the fluid above the piston is forced upwardly through ports 54 in a part of 65 the housing member E, thence under a circular check valve 55 into an annular space between the tube 2 and the housing member E. It then continues moving upwardly between the tube 2 and the tube 42 and meets and mixes with the motive fluid discharged from the motor issuing from under the circular check valve 46 (Fig. 2).

On the downward movement of the pump piston D the circular check valve 52 closes and the fluid passes downwardly through diagonal 75

ports 56 in the housing member F from which it escapes through a circular check valve 57 into the annular space lying between the tube 2 and a tube 58 extending from the housing member 5 F to the housing member E. After it reaches the housing member E it passes upwardly between the tube 2 and the tube 42 and mixes with the exhaust motive fluid from the motor as before. During the downward stroke of the pump piston 10 D fluid is drawn into the space above the pump piston through the central passage 4, up through diagonal ports 59 in the housing member F, and upwardly through the annular space between the pump cylinder 53 and the tube 58. It then passes 15 under a circular check valve 60 into the space above the pump piston D.

It will therefore be seen that the pump is double acting and at each stroke draws fluid from the well to that side of the piston at which the 20 cylinder space is increasing and discharges fluid from that side of the piston where the cylinder space is decreasing and forces it upwardly where it mixes with the motive fluid discharged from the motor. Heretofore double acting pumps 25 could not be used in oil wells due to the great inertia of the mechanical parts and particularly the inertia of the string of rods extending down the well to the pump piston. However, as I eliminate these moving mechanical parts the 30 pump can be a double acting one.

In water wells, or oil wells, where there are no formation gases to be handled, the pump and motor may be suspended from one string of tubing only in which case a packer should be placed 35 just below the pump so that the fluid pump from the well and the fluid exhausted from the motor will be forced upwardly in the annular space between the well casing and the tubing which supports the apparatus and through the center 40 of which the motive fluid is supplied to the motor.

While my improved method of pumping oil from wells contemplates the forcing of oil down the string of tubing to the motor to serve as motive fluid, the details of the equipment necessary to effect this form no part of the invention. Any suitable equipment may be used for this purpose. The motive fluid oil may be pumped from any convenient location and conducted to a group of wells thus eliminating the necessity 45 of an individual engine and the other usual equipment at each well. Of course, the oil pumped to the wells, should be clean and the sand and water settled out of it. The wear on the parts of the apparatus will be negligible as the oil used for the motive fluid will lubricate all of the moving parts and will protect the metal from corrosion.

The column of fluid in the induction tubing leading down to the motor will balance the column of fluid of equal height made up of exhaust motive fluid and the fluid pumped from the well. Therefore, each pound of pressure in the induction tubing, at the discharge elevation of the eduction tubing, will deliver a pound of 60 pressure differential on the motor piston, less friction due to the flowing stream. Therefore a gauge pressure of 1000 lbs. per square inch in the induction tubing, at the discharge elevation of the eduction tubing, will represent 1000 65 lbs. of pressure per square inch on the motor piston above that resulting from back pressure of the column of fluid in the eduction tubing, less friction due to the flow. The hammering and jerking effects on the rods, tubing and pumping 70 equipment experienced in present installations,

and which ultimately cause break downs of the equipment as well as wear and tear on the parts are entirely eliminated. In my method and apparatus the pressure is practically steady, and not intermittent, and there will be no losses due 5 to stretch as above explained.

The efficiency of my new method and apparatus exceeds the conventional ones now in use and has a capacity of many times that of other deep well pumping methods and apparatus hereto- 10 fore used.

While the apparatus herein described was designed especially for pumping fluid from wells, and primarily for pumping oil from oil wells, it may be used for other purposes, especially 15 where a reliable fluid operated motor is needed having such size and shape that it may be installed in a limited space, or where there is needed a combination of a reliable fluid operated motor and a pump, both of such size and shape that 20 they may be installed in a limited space, such as exists in an oil well.

I claim:

1. In a fluid actuated deep well motor for operating a deep well pump having a reciprocating 25 plunger, a reciprocating piston, means for coupling said piston to the plunger of the pump, an inlet valve and an exhaust valve for said motor, a valve actuating auxiliary fluid motor having a reciprocating piston for actuating said first 30 named valves and connected thereto, an inlet to and an outlet from said last mentioned piston, a slideable pilot valve for controlling said inlet to and outlet from said last named piston, a pilot 35 valve actuating rod connected to said first named piston and adapted to reciprocate therewith, means for actuating said pilot valve with said rod, and linkage between said pilot valve and said first named valves for controlling the movement of said pilot valve.

2. A motor as claimed in claim 1, and wherein said linkage includes a toggle joint with the members thereof held under a restricted compression.

3. In a fluid actuated motor for operating a deep well pump having a reciprocating plunger, 45 a reciprocating piston, means for coupling said piston to the plunger of the pump, a sleeve valve for controlling the inlet and exhaust to and from said fluid motor, an auxiliary fluid motor having inlet and outlet ducts and having a reciprocating 50 piston connected to said sleeve, a slideable pilot valve in communication with said inlet and outlet ducts and concentric with said sleeve valve, a pilot valve rod concentric with said pilot valve and connected to said first named piston and 55 adapted to reciprocate therewith, co-acting mechanical means between said pilot valve and said pilot valve rod for actuating said pilot valve with said rod, and linkage between said pilot valve and said first named valve for controlling the 60 movement of said pilot valve.

4. In a fluid actuated motor for operating a deep well pump having a reciprocating plunger, a reciprocating piston, means for coupling said piston to the plunger of the pump, a sleeve valve 65 for controlling the inlet and exhaust to and from said fluid motor, an auxiliary fluid motor having inlet and outlet ducts and having a reciprocating piston connected to said sleeve valve, a slideable pilot valve in communication with said 70 inlet and outlet ducts and concentric with said sleeve valve, a pilot valve rod concentric with said pilot valve and connected to said first named piston and adapted to reciprocate therewith, and co-acting mechanical means between said pilot 75

valve and said pilot valve rod for actuating said pilot valve with said rod, said auxiliary motor being positioned between the pilot valve and said first named piston, and said pilot valve rod being passed through said auxiliary motor and through and concentric with said piston thereof.

5. In a deep well motor for a well pump, a slide valve therein, an auxiliary fluid motor having a piston chamber and a reciprocating piston therein for operating said slide valve, motor fluid conveying pipes attached to said slide valve and extending to said piston chamber and affixed to said piston and opening one on either side thereof, and a pilot valve adjacent to and concentric 10 with said slide valve and in communication with said motive fluid conveying pipes for controlling the motive fluid to and from said auxiliary motor.

6. In a fluid actuated deep well motor for operating a deep well pump having a reciprocating 20 plunger, a piston, a slide valve therefor, an auxiliary valve actuating fluid motor, a reciprocating piston therefor connected with said valve, slide motive fluid conveying ducts mounted on said last named piston and opening one on either 25 side thereof and with said ducts also connected to said first named valve and opening therefrom into a pilot valve controlled passageway,

and a pilot valve in said passageway and operatively connected with said first named piston.

7. In a fluid actuated deep well motor for operating a deep well pump having a reciprocating plunger, a sleeve valve for controlling the 5 inlet and exhaust to and from said fluid motor, an auxiliary fluid motor connected to said sleeve valve for actuating the same and having a pilot valve concentric with said sleeve valve and slidably therein for controlling the inlet and exhaust 10 to and from said auxiliary motor, and means for actuating said pilot valve, including a pilot valve rod connected to said first named piston and slidably passed thru said pilot valve and slidably extending into a spring retaining cage, a collar 15 on said rod in said cage, a spring retaining cage on said pilot valve, and coil compression springs in said cage and about said rod and located one on either side of a collar on said rod and with said springs each abutting said cage and said 20 collar.

8. In a motor as claimed in claim 7, linkage including a toggle joint between said pilot valve and said sleeve valve, and means for placing the members of said toggle joint under a restricted 25 compression.

CHARLES C. CARLISLE.
